FOLDING UTILITY LUNCH TRAY

John C. Thomson, Ansonia, Conn., assignor to
 The Beaverbrook Moulding Company, Ansonia,
 Conn., a corporation of Connecticut

Application May 5, 1950, Serial No. 160,232

1 Claim. (Cl. 211—88)

1

This invention relates to lunch trays of the type having supporting brackets or hangers, and more particularly to a tray of the above nature which may be folded into a compact form to facilitate storage or shipment of the tray when not in use.

One object of this invention is to provide a tray of the above nature which comprises frictional means for holding the tray in a flat condition when unfolded.

Another object is to provide a tray of the above nature which when in flat condition will present a smooth unbroken upper surface, and in which the joint between the foldable sections thereof will be substantially fluid tight.

A further object is to provide a tray of the above nature which will be simple in construction, inexpensive to manufacture, easy to install and manipulate, compact, ornamental in appearance, and very efficient and durable in use.

With these and other objects in view, there has been illustrated on the accompanying drawing one form in which the invention may conveniently be embodied in practice.

In the drawing,

Fig. 1 is a perspective view showing the improved lunch tray as it would appear when unfolded and in condition for use, and also showing in broken lines an object upon which the brackets are engaged for supporting the tray.

Fig. 2 is a front view of the tray as it would appear from the line 2—2 of Fig. 1.

Fig. 3 is an end view of the same, as it would appear from the line 3—3 of Fig. 2.

Fig. 4 is a bottom view of the same as it would appear from the line 4—4 of Fig. 2.

Fig. 5 is a bottom view similar to Fig. 4, but showing the supporting brackets folded under the tray.

Fig. 6 is a rear view on an enlarged scale, showing the tray completely folded or collapsed.

Fig. 7 is a fragmentary rear view illustrating the hinge construction as it would appear at an intermediate stage in its range of movement.

Referring now to the drawing in which like reference numerals denote corresponding parts throughout the several views, the numerals 10 and 11 indicate a pair of complementary tray sections of equal size and of generally rectangular shape, the front outer corners of said sections preferably being rounded as shown at 12 and 13.

The sections 10, 11 are provided respectively with flat upper surfaces 14, 15 which are each surrounded upon three sides by upstanding rims 16, 17, said sections being so constructed that when the tray is unfolded as shown in Fig. 1 the

2

flat surfaces 14, 15 will be coplanar and the rims 16, 17 will extend continuously around the periphery of the tray.

The tray sections 10, 11 are swingably connected by means of a hinge construction comprising a laterally projecting pair of lugs 18, 19 formed integrally on the bottom of the section 10 adjacent opposite edges thereof, and a similar pair of lugs 20, 21 integrally formed with the section 11, the latter pair of lugs, however, being arranged to overlap the lugs 18, 19 upon their inner surfaces.

The pairs of lugs 18, 19, and 20, 21 extend beneath abutting ends 22, 23 of the tray sections 10, 11 and are apertured to receive a transverse hinge pin 24 which is located directly below said abutting ends.

As a means for holding the sections 10, 11 in flat unfolded condition, the lugs 18, 19, 20, 21 are each formed with a peripheral upper cam portion 25 (Figs. 6 and 7) which is eccentrically disposed with respect to the hinge pin 24. The cam portions 25 are so located as to engage the lower surfaces of the tray sections 10, 11 as said sections approach a coplanar relationship, so that when the tray is in a flat condition, said cam portions will have a firm frictional engagement with the lower surfaces of the sections, and thus will prevent accidental folding of the tray during use.

In order to support the tray during use, the lower surfaces of the sections 10, 11 are formed with respective pairs of aligned horizontally apertured lugs 26, 27, each of said pairs of lugs being located between the centers of the respective sections and the outer ends of said sections.

Provision also is made of a pair of heavy wire S-shaped hangers or brackets 28, 29, comprising horizontal shaft portions 30, 31 which are held frictionally in the lugs 26, 27. The rear ends of the shaft portions 30, 31 are bent at right angles and then in a reverse direction to form hook portions 32, 33 having downturned ends 34, 35. The ends 34, 35 are flattened in order to permit them to be inserted in a narrow space or groove in a supporting object.

The shaft portions 30, 31 are of a sufficient length to permit them to be retained in the lugs 26, 27 when said shaft portions are slid rearwardly to positions which will permit the hook portions 32, 33 to be swung upwardly and engaged over a support A, as shown in broken lines in Fig. 1.

The tray sections 10, 11 are preferably molded from a suitable stiff plastic material having a

high dimensional stability, so that the abutting edges 22, 23 may be very accurately formed in such a manner as to provide a tight joint which will substantially prevent any leakage of fluid therethrough when the tray is in a flat condition.

In order to permit the tray sections 10, 11 to have a thin cross section and thus conserve material, the lower surfaces thereof may be provided with reinforcing ribs 36, 37, said ribs being interrupted in order to provide clearance for longitudinal sliding of the shaft portions 30, 31 of the hangers or brackets 28, 29.

Operation

In operation, the tray in its unfolded flat condition shown in Fig. 1 will have the hangers 28, 29 engaged over a supporting object A (Fig. 1), or over any other object having a suitable supporting ridge or groove such as the edge of an automobile window opening or a piece of furniture. The tray will then serve as a convenient support for objects such as dishes placed thereon. If liquids should be spilled upon the tray, the peripheral rims 16, 17 will confine the spilled liquid to the tray, and the liquid-tight joint at the abutting edges 22, 23 of the tray section will prevent the escape of any liquid therethrough.

The predominant loads upon the tray will ordinarily be applied at points between the pairs of bracket attaching lugs 26, 27, thus tending to hold the tray in flat condition. However, the frictional engagement of the hinge lugs 18, 19, 20, 21 with the lower surfaces of the tray sections will prevent accidental collapse of the tray in the event that the load should become shifted to the outer ends of the tray.

When the tray is no longer needed, the hangers 28, 29 may be swung downwardly and then slid inwardly beneath the tray sections as shown in Fig. 5, after which said tray sections may be folded or collapsed as shown in Fig. 6, for facilitating storage or shipment.

While there has been disclosed in this specification one form in which the invention may be embodied, it is to be understood that this form is shown for the purpose of illustration only, and that the invention is not to be limited to the

specific disclosure but may be modified and embodied in various other forms without departing from its spirit. In short, the invention includes all the modifications and embodiments which come within the scope of the following claim.

Having thus fully described the invention, what is claimed as new, and for which it is desired to secure Letters Patent is:

10 In a foldable utility tray, a pair of complementary flat tray sections adapted, when unfolded, to be disposed in horizontal edge-to-edge aligned relationship, said tray sections being hingedly connected together by two pairs of juxtaposed, 15 overlapping lugs extending downwardly therefrom, a single transverse hinge pin mounted in said lugs and located below the abutting adjacent edges of said tray sections, the lugs on each tray section having eccentric cam portions on their 20 peripheries frictionally engaging the lower surface of the other tray section when the inner adjacent edges of said tray sections are in abutment, said cam portions assisting in holding the tray sections in flat, horizontal alignment, and 25 slideable and twistable tray-supporting hook brackets pivotally attached to each of said tray sections adjacent the outer ends thereof, whereby the weight of articles on the center of said tray will tend to hold it in flat condition.

JOHN C. THOMSON.
